ELECTRICAL COUPLING SWITCH

Ervin Mestitz, Llandaff, Cardiff, South Wales

Application March 1, 1946, Serial No. 651,214
In Great Britain February 23, 1945

2 Claims. (Cl. 200—51)

1

This invention relates to combined coupling switches and has for its object to provide a rotary switch on a coupling secured to a cable and suitable for connection to electric appliances such as pressing irons, kettles, toasters and the like. Whilst it has been known heretofore to provide switches on appliances and on wall sockets a combined coupling switch according to this invention has the advantage that the same cable with the coupling switch can be used for a variety of appliances and that the switch is at a suitable distance from the hot appliance to which the coupling is connected. The rotary switch has no projecting press button and is not liable to be inadvertently operated.

An electrical coupling according to this invention therefore comprises terminals for cable connection, coupling contacts and a rotary switch connected between one of the said contacts and one of the said terminals, the terminals, contacts and switch being held in a common casing consisting of two shell shaped parts. The said shell shaped parts can be of identical outer surface, and an operating knob of the switch can be so engaged by the ends of the shell shaped parts that the knob is rotatably held by the said parts and cannot move in an axial direction.

Another object of the invention is to provide a spring between the operating knob of the switch and a rotatable switch contact in such manner that the spring serves for pressing the rotatable contact piece against its counter contact and also for ensuring a quick make and break action. The main body of the coupling can be torpedo shaped and the operating knob of the switch can be arranged at one end whilst the cable entry is at the other end of the torpedo shaped body.

More details will be apparent from the drawings which illustrate diagrammatically by way of example preferred embodiments of the invention.

Figure 1 shows one part of the casing of a coupling with the rotary switch and electrical connections arranged in it.

Figure 2 is a top view of the coupling showing the dividing line between the two parts of the casing.

Figures 3 and 4 show on a larger scale details of the switch construction.

Figure 3 is a section along the line A—A viewed in the direction of the arrow *a* and shows the insulating support for the stationary counter contacts, whilst Figure 4 shows the movable contact piece and its connection to the operating knob.

The combined coupling switch comprises an elongated casing whose main portion 1 housing

2

the rotary switch is of torpedo-, cigar-, or similar shape, a cylindrical projection 2 being provided to hold the coupling contacts 12, 13. The casing is subdivided into two shell like parts 3, 4 whose surfaces are preferably of identical shape. The casing can be made of any material which is known in the art for the casing of electrical apparatus, particularly insulating material, e. g. resinous moulding material, hard rubber, the material which is known under the trade-mark Mycalex and the like. The two parts 3, 4 of the casing are connected together by means of bolts reaching through holes 5, 6, or by screws reaching through holes in one part and engaging threaded inserts in the other part of the casing. The coupling contacts 12, 13 can be provided with shoulders 14 or the like to be gripped and held in position between the recessed faces 15 of the two parts 3, 4 when they are pressed against each other. Instead of pin contacts as shown in the drawings contacts of tubular or any other shape known in the art can be used. Apart from the said recesses for the coupling contacts the joining faces 15 of the parts 3, 4 can be plane as shown in the drawings or one of the faces can be provided with a groove and the other one with a projection, and gaskets or packings can be used for water tight joints.

The rotary switch is arranged in series with the contacts 13. The stationary contacts 23, 24 of the switch are respectively connected via an intermediary conducting member 21 to the coupling contact 13 and via a lug 10 to one wire 20 of a two cored cable 16 whose other wire 19 is connected direct to the other coupling contact 12.

Both the lug 10 and the coupling contact 12 are provided with suitable terminals for cable connection. Undesirable stresses on these terminals are prevented by cable gripping means 17 as is known in the art.

The stationary switch contacts 23, 24 are supported by a suitable insulating piece 25 which may be integral with the shell like part 3 of the casing and in which the fixing holes 5, 6 are provided. The stationary contacts, preferably of Phosphor bronze, are slightly concave and securely held in recesses 30 and slots 31 of the insulating piece 25 (Figure 3). Shallow recesses 32 similar in shape to the shallows of the stationary contacts 23, 24 are provided in the insulated piece 25 and positioned at right angles to the cylindrical shallows in the said contacts 23, 24.

The movable contact bridge is formed by a bar or rod 26 e. g. of Phosphor bronze secured to a spindle 27 which is guided in a hole 33 of the in-

sulating piece 25 (Figure 3) and in a hole 34 of an operating knob 28 of insulating material, e. g. a resinous moulding material. A helical spring 29 provides a resilient connecting member between the spindle 27 and the knob 28. One end of the spring is secured to the spindle and may reach through a radial hole of the spindle, and the other end of the spring is secured to the knob 28 and may reach into an axial hole of the knob. The rotatable part of the switch and particularly the knob 28 is supported by the edges of the shell like parts of the casing which form a circular bearing engaging a groove 35 of the knob 28.

It will be understood that the spring 29 thus serves for pressing the switching bar against its stationary counter contacts 23, 24 and also for moving it abruptly to ensure a quick make and break action. If the knob is turned in a clockwise direction the switching bar 26 does not move with the knob until the torsional force of the spring 29 overcomes its axial pressure, then the switching bar 26 is lifted out of the shallows of the counter contacts 23, 24 and moves abruptly to the shallows 32 of the insulator 25, or the switching bar is lifted out of the shallows of the insulator and moves abruptly into the shallows of the counter contacts. The elastic power accumulated in the spring 29 whilst the knob 28 is turned before the bar 26 is moved accelerates the movement of the said switching bar when it starts moving and thus affords the quick make and break action. The magnitude of the torsional power and of the pressure between the co-operating contacts can be adjusted by the pretension of the spring.

The operating knob 28 and the casing can be marked at 36, 37 and 38 to indicate the "on" and "off" positions of the switch.

Variations are possible without departure from the invention. The insulating piece supporting the stationary switch contacts need not be integral with the casing and may form a separate piece which is held in position between the two shell like parts of the casing. The cable may be sheathed with rubber, artificial rubber and the like and the sheathing may be joined to the casing of the coupling or to a sheathing of the coupling of similar material from which the operating knob projects.

I claim as my invention:

1. Electrical coupling comprising a two-part

casing, terminals for cable connection, and coupling contacts, wherein a rotary switch connected between one of the contacts and one of the terminals is formed by a contact bridge rigidly secured to a spindle which is slidable and guided in an operating member projecting outside the casing, the said spindle and member being connected together by a spring for transmitting an axial pressure in the rest positions of the switch and a substantial torque for the quick contact making and breaking action, the operating member being rotatably supported by a projection of the casing fitting into a circular groove of the said member to exert the axial contact pressure via the spring and slidable spindle.

2. Electrical coupling comprising a casing of torpedo shape divided in an axial plane, a cable entry hole at one end of the torpedo shaped casing, a terminal for cable connection forming a unitary structure with one coupling contact, a rotary switch connected between the other terminal for cable connection and the other coupling contact consisting of a contact bridge rigidly fixed to a spindle which is slidable and guided in an axial bore of an operating member projecting outside the casing, a spring connecting the said spindle and operating member to transmit an axial pressure in the rest positions of the switch, and a substantial torque sufficing to produce a quick contact making and breaking action when the operating member is rotated, the operating member being arranged to pass through a circular opening which is co-axial with the cable entry at the opposite end of the torpedo shaped casing and whose edge projects into a circular groove of the operating member to exert the axial pressure.
